UNITED STATES PATENT OFFICE

EDWARD KANTER, OF CLEVELAND HEIGHTS, OHIO

DESIGN FOR A DISPENSING DEVICE

Application filed October 12, 1931. Serial No. 41,366. Term of patent 3½ years.

To all whom it may concern:

Be it known that I, EDWARD KANTER, citizen of the United States, residing at Cleveland Heights, in the county of Cuyahoga, and State of Ohio, have invented a new, original, and ornamental Design for Dispensing Device, of which the following is a specification, reference being had to the accompanying drawings, forming part thereof, wherein Fig. 1 is a front elevation and Fig. 2 a top plan view of a dispensing device illustrating my new design.

I claim:—

The ornamental design for a dispensing device, as shown.

EDWARD KANTER.
